UNITED STATES PATENT OFFICE.

HENRY ALEXANDER, OF NEW YORK, N. Y., ASSIGNOR TO THE UNIVERSAL BRUSH COMPANY, OF TROY, NEW YORK, A CORPORATION OF NEW YORK.

DESIGN FOR A BRUSH-DISPLAY STAND.

41,638.

Specification for Design.

Patented Aug. 1, 1911.

Application filed April 29, 1909. Serial No. 493,047. Term of patent 14 years.

To all whom it may concern:

Be it known that I, HENRY ALEXANDER, a citizen of the United States, residing at New York city, in the county of New York and State of New York, have invented a new, original, and ornamental Design for Brush-Display Stands, of which the following is a specification, reference being had to the accompanying drawing, forming part thereof.

The single figure of the drawing is a view

in perspective, as seen from the rear, of a brush-display-stand embodying my design.

At 1, is represented a hair-brush.

I claim:—

The ornamental design for a brush-dis-
play-stand, as shown and described.

HENRY ALEXANDER.
